Letters Patent. Mar. 1. 1834.

The Schedule referred to in these Letters Patent, and making part of the same, containing a description in the words of the said Benjamin Franklin Stickney, himself of his improvement called the Agricultural Pulverizer.

To all to whom these presents shall come. Be it known that I Benjamin Franklin Stickney, of Kalamazoo County of the State & Territory of Michigan, have invented a new and useful improvement in Agriculture consisting of a machine to which he has given the name of Agricultural Pulverizer, intended to be used in the tillage of ground by a revolving perpendicularly of cutters or hoes by which the earth weeds, stones & roots &c. in the earth or on the surface are cut fine removed & finely pulverized performing all the offices now performed by the plough, harrow &c. and in a more perfect manner & great saving of labour & that the following is a full & exact description of the construction & operation of the said Machine as invented by me.

Fig. 1. of the accompanying drawings A.A. two wheels to roll on the ground which by a horse harnessed to the shafts B.B. for draft, constitutes the original moving power to propel the Machine. C. a cog-wheel confined to the same axle of the wheels A.A. D. a burr into which cog-wheel C. sticks & is immediately fixed to a shaft on which is cog-wheel E. this wheel sticks in to burr D. on the shaft of which is a cylinder G. to the periphery of which is attached a row of iron hoes or cutters, extending the whole length of the cylinder attached to the surface playing inward making a joint that admits the hoe to fall back but no further forming thus a tight line from the centre to the circumference. This is effected by a slot at the joint of the stroke before

and

R.D.

and behind the latter fastened with a plate on the surface of the cylinder of a small lantern of the kind used for oil lamps, so that the light may be thrown out from the lantern in the direction of the rear wheel, so that the lantern may move in the opposite direction from that in which the machine moves. There are two gears that appear more distinctly in the view Fig. 3, B, is the rear moving on the same center as the cog wheel E in Fig. 3, A, by which the cylinder can be raised and suspended without affecting the rearing of the machine. The proportions of the parts may be made to suit the operator. The proportions of the vehicle are 6 feet in diameter by a wheel 6 feet 6 inches broad, 3 inches cog wheel E, 6 feet 6 inches & the proportions of the circle described in the revolutions of the wheel 6 feet.

It is proposed that if the smooth surface of the wheel that rolls on the ground should be found not to revolve so easily as to be liable to be ground to the first point of contact to project from the surface to bring it in contact with iron plates or attack dogs that should prevent the sliding of the wheels.
